UNITED STATES PATENT OFFICE

114,167

DESIGN FOR A SWIVEL TYPE CLOSET BOWL AND MOUNTING THEREFOR

Leif Andersen and Edward A. Fredrickson, Chicago, Ill., and Hugh R. Van Sciver, Trenton, N. J., and Roy H. Zinkil, Oak Park, Ill.

Application June 18, 1938, Serial No. 77,922

Term of patent 14 years

To all whom it may concern:

Be it known that we, Leif Andersen, Edward A. Fredrickson, Hugh R. Van Sciver and Roy H. Zinkil, citizens of the United States, the said Andersen residing at East 110th and South Cottage Grove Avenue, in the county of Cook, city of Chicago, State of Illinois; the said Fredrickson residing at 5956 Manton Avenue, in the county of Cook, city of Chicago, State of Illinois; the said Van Sciver residing at 309 N. Clinton Avenue, in the county of Mercer, city of Trenton, State of New Jersey, and the said Zinkil residing at 406 N. Cuyler Avenue, in the county of Cook, village of Oak Park, State of Illinois, have invented a new, original, and ornamental Design for a Swivel Type Closet Bowl and Mounting Therefor, of which the following is a specifica-

tion, reference being had to the accompanying drawings, forming part thereof.

Fig. 1 is a side perspective view of the swivel closet bowl and mounting therefor showing our new design.

Fig. 2 is an opposite side perspective view of the swivel closet bowl and mounting therefor.

Fig. 3 is a plan view of the swivel closet bowl and mounting therefor.

We claim:

The ornamental design for a swivel closet bowl and mounting therefor, substantially as shown.

LEIF ANDERSEN.
EDWARD A. FREDRICKSON.
HUGH R. VAN SCIVER.
ROY H. ZINKIL.
